UNITED STATES PATENT OFFICE

FRED E. BRUNELL, OF PLATTSBURG, NEW YORK

COLLAPSIBLE BASKET

Application filed August 30, 1928. Serial No. 303,052.

The present invention relates to improvements in receptacles and has reference more particularly to a basket that can be collapsed into relatively small compass so that when in a folded condition will not occupy any considerable amount of space, said basket being capable of being set up in position for use whenever necessary.

A further object is to provide a collapsible basket which is simple in construction, inexpensive, strong and durable and further well adapted to the purposes for which it is designed.

Other objects and advantages will become apparent during the course of the following description.

In the accompanying drawing, forming a part of this specification, and in which like numerals indicate like parts throughout the same:

Figure 1 is a bottom plan view of the collapsible basket embodying my invention, showing the same in its assembled position;

Figure 2 is a side elevation thereof, and

Figure 3 is an end elevation;

Figure 4 is a top plan of the basket, in its collapsed or folded position;

Figure 5 is a side elevation of the basket in its collapsed position, and

Figure 6 is a detail perspective view of the U-shaped unit.

In the drawing wherein for the purpose of illustration is shown a preferred embodiment of my invention, the numeral 1 designates generally my improved collapsible basket the same including upper and lower substantially rectangular shaped wire frames denoted by the reference characters 2 and 3 respectively.

The means for spacing the top and bottom frames with respect to each other when the basket is assembled for use will be presently described. The basket further includes a burlap covering for the bottom, sides and end of the basket, said covering being denoted by the reference character 4 and the upper edges of the burlap covering are secured to the sides and ends of the upper frame 2 in any appropriate manner. Also forming a salient part of the present invention is the

substantially U-shaped wire unit 5, the base portion 6 thereof extending transversely across the bottom of the frame 3 at the intermediate portion thereof while the arms 7 and 8 extend upwardly along the outer sides of 55 the burlap covering.

The upper ends of the arms are bent back upon themselves to form elongated loops 9 that slidably engage with the respective sides of the upper frame 2 as suggested in Figure 60 3 and furthermore these elongated loops permit the collapsing of the basket and it is to be also understood that the base portion 6 is not welded or otherwise fixedly attached to the respective sides of the bottom frame 3 65 so that this U-shaped unit 5 will be disposed in a diagonal position when the basket is collapsed.

The collapsible basket further includes the provision of a pair of end bracing units 70 denoted by the reference character 10 and each unit comprises a pair of strands of wire that have their intermediate portions twisted together to form the vertically disposed shank 11, the lower ends of these strands of wire 75 extending outwardly from the shank 11 in diverging relation as at 12 and 13 respectively and the free ends thereof are bent around the respective ends of the bottom frame 3 as at 14.

The upper ends of the strands of wire of each end unit extend upwardly in diverging relation from the twisted shank 11 as at 15 and 16 respectively and the free ends of the diverging portions 15 and 16 are bent to form 85 eyes 17 that engage around the respective ends of the top frame 2 adjacent the sides of said top frame as clearly suggested in Figure 3.

The eye portions 14 and 17 further constitute a hinge connection between the end unit and the top and bottom frame and when the parts are arranged as shown in Figures 1 and 3 inclusive, the basket is assembled and 95 will be open at its top to receive various articles. When not in use, the basket can be collapsed or folded to small compass without occupying any considerable amount of space so that said basket can be shipped more 100

easily and handled more efficiently than a non-collapsible basket.

Furthermore a collapsible basket of the above mentioned character will be strong and durable and very inexpensive in its manufacture.

While I have shown the preferred embodiment of my invention, it is to be understood that various changes in the size, shape and arrangement of parts may be resorted to without departing from the spirit of the invention and the scope of the appended claim.

Having thus described my invention, what I claim as new is:

15 In a collapsible basket, spaced top and bottom frames, a covering for the bottom, sides and ends of the basket, end units pivotally connected to the respective ends of the top and bottom frames, and an additional unit for association with the intermediate portions of the sides of the top and bottom frames, said last mentioned unit comprising a U-shaped structure having the base portion thereof extending across the bottom frame at the intermediate portion thereof, the arms of the U-shaped structure extending upwardly from the sides of the frame, the upper ends of the arms being slidably and pivotally associated with intermediate portions of the respective sides of the top frame.

30 In testimony whereof I affix my signature.
FRED E. BRUNELL.
